UNITED STATES PATENT OFFICE.

JAMES E. PHILLIPS, OF CLEVELAND, OHIO.

CALENDAR.

1,288,167.

Specification of Letters Patent.

Patented Dec. 17, 1918.

Application filed January 8, 1918. Serial No. 210,105.

To all whom it may concern:

Be it known that I, JAMES E. PHILLIPS, a citizen of the United States, residing at Cleveland, in the county of Cuyahoga and 5 State of Ohio, have invented certain new and useful Improvements in Calendars, of which the following is a specification.

This invention relates to calendars, and more particularly to a device used for the 10 purpose of attaching the date sheets of calendars to the backing members.

Heretofore the ordinary calendars, used 15 particularly for advertising purposes and distributed gratis, have comprised a backing member of bristol board, the date sheets being attached to said backing member either by adhesive, wire staples, or by stitching with thread or fine wire. In the usual form the backing member covers the 20 entire back of the date sheets and extends more or less above said sheets, the exposed portion being utilized for advertisements. If the calendar is a monthly calendar, which is the most common type, at the end of each 25 month a date sheet is torn off. There are numerous objectionable features common to the majority of calendars of this character, principally in the matter of economy and convenience. Calendars constructed in the 30 common ordinary way are not durable, and therefore they do not fulfil their intended purposes, as a lasting advertisement or as a ready date reference medium for the entire year. The tearing off of one sheet is liable to 35 dislodge several sheets, and frequently the whole pad is separated from the backing and destroyed, the life of a calendar being generally only a few months at the most. The improved attachment, when embodied 40 in a calendar eliminates the objectionable features. It provides for economy in material, facilitates the mailing of the calendar, and enhances its service and durability. These and other advantageous features will 45 be apparent from the following description, reference being had to the accompanying drawing which is made a part of the specification, and in which similar characters are employed to designate corresponding parts.

50 In the said drawing Figure 1 illustrates a calendar embodying the improved attachment, a portion of the date sheets being broken away for convenience of explanation.

Fig. 2 is a side view of the attachment and 55 shows fragments of the backing member and date sheets in vertical section in their rela-

tive positions as assembled, one element of the attachment being also in section.

Fig. 3 is a view of a resilient washer which is an element of the attachment.

Fig. 4 is a fragmentary, sectional view of a modification of the improvement.

The preferred form of the improvement as best shown in Fig. 2, comprises a member, made preferably of steel wire, having a straight portion 1, with a bend at 2 which forms a spring loop, the part 3 being bent back toward the part 1. A reverse bend 4 and the shank 5 form a hook with two opposing bends 6 and 7 therein. A resilient washer 8 is provided, the said washer being preferably made of thin rubber having an aperture 9 punched therein and adapted to be forced on and off of the shank 5.

A calendar embodying the improved attachment, includes a back member 10 made of stiff bristol board or similar material, provided with two or more apertures 11 in horizontal alignment. The improved attachments are connected with the member 10 by passing the member 1 through an aperture 11 and pressing the device downward until the bend 2 rests in said aperture. The peculiar back-bend of the member 3 co-acting with the straight member 1 causes the member 10 to be clamped between said members 1 and 3, thereby retaining the attachment firmly on the calendar back member.

The date sheets 12 are provided with two or more apertures 13 in horizontal alignment, so spaced that they will register with the shanks 5 of the attachments when said attachments are in their proper position on the back member 10. This allows the apertures 13 to engage the attachments and rest in the bends 4, the date sheets depending freely from the attachments. After the desired number of sheets have been strung on the hangers, the resilient washers 8 are forced onto the shank members 5, thereby retaining the sheets in compact condition and preventing their tearing or dislodgment by wind or other extraneous forces.

It is obvious that the improved attachments provide economy in material, as both sides of the date sheets may be utilized for printing the date schedules, thereby creating a saving of 50% on that item alone. Another economical feature which is also a factor of convenience, is made possible by the improved attachment, as will be clearly understood from the following.

In the ordinary calendars where the date sheets are attached directly to the back member by adhesive or stitching, it is essential for the said back member to extend down 5 the full width of the date sheets as a protection to said sheets in handling, particularly in going through the mail. In mailing the larger sizes of calendars it has been necessary to roll and insert them in tubes, 10 which are more or less expensive as compared to ordinary envelopes. By using the improved attachments in a calendar make up, the backing member may be made the same dimensions in length and breadth as 15 the individual date sheets. For mailing or otherwise distributing, the date sheets are detached from the back member, laid flat thereon and inclosed, with the necessary number of attaching devices in an envelop, 20 making a flat non-cumbersome package, and not disfiguring the calendar. This reduces the quantity of backing material substantially one-half, making a great saving in shipping charges and eliminating the extra 25 expense of the mailing tubes. It also provides for the extended use from year to year of the same back member and attachments, new date sheets being furnished by the dealer, publisher or advertiser each year. 30 This is a very desirable feature, as an elaborate, ornamental, more or less expensive back member worthy of preservation for perpetual use may be made of durable material and preserved as an ornament or a lasting 35 advertisement, by supplying at small cost fresh date sheets annually.

Another valuable feature of convenience is provided by the removal and replacement 40 of the date sheets. Calendar date sheets are frequently provided with spaces for recording data, or making memorandum notes. With the ordinary calendars hanging on the wall, it is inconvenient to make the notations, but with the improved attachment, 45 the sheet may be removed, the notation con-

veniently made thereon and said sheets replaced undamaged on the hangers.

The modification shown in Fig. 4 provides for an attachment with a straight shank 5^a having a head 1^a which bears on 50 the back member 10, the shank 5^a extending through an aperture in said back member. The date sheets are strung on the shank 5^a, and the resilient washer forced onto said shank for the purpose hereinbefore set forth. 55

Having now described my invention, what I claim and desire to secure by Letters Patent is:

1. As a new article of manufacture a date sheet attachment for calendars, including a 60 hanger member removably attached to the calendar back, an extending shank on said hanger which engages the date sheets, and a resilient retaining washer adapted to be 65 forced on and off of said shank.

2. A date sheet attachment for calendars, including a hanger provided with a spring clamp for removable attachment to the calendar back, a shank which engages the date sheets, and a resilient retaining washer removably connected with said shank. 70

3. A date sheet attachment for calendars, comprising a wire member bent so as to form a spring clamp adapted to grip the calendar back through an opening in said 75 back, a reverse bend in said wire member forming a hanger for engagement in an aperture in the date sheets, and a resilient washer for retaining the sheets in engagement with the hanger. 80

4. In a calendar, the combination of a back member provided with apertures therein; hanger members removably engaging said back member through the apertures; date sheets provided with apertures that engage the hangers; and resilient washers for retaining said date sheets in engagement with the hangers. 85

In testimony whereof I affix my signature.
JAMES E. PHILLIPS.
